UNITED STATES PATENT OFFICE.

JOHN H. MAGEE, OF CARTHAGE, MISSOURI.

JIG.

1,128,807.

Specification of Letters Patent.

Patented Feb. 16, 1915.

Application filed July 13, 1908. Serial No. 443,325.

To all whom it may concern:

Be it known that I, JOHN H. MAGEE, a citizen of the United States of America, residing at Carthage, in the county of Jasper and State of Missouri, have invented certain new and useful Improvements in Jigs, of which the following is a full, clear, and exact description, reference being had to the accompanying drawing, forming part of this specification.

My invention relates to that class of jigs used in handling ores, coal or other materials which contain constituents of different specific gravity, and the invention has for its object the provision of improved means whereby the entire top stratum of material being jigged may be moved forwardly in the jig continuously and intermittently in a horizontal direction toward the discharge end of the jig independent of the means used to stratify the material and out of conflict with such means. It is a well known fact that in the use of jigs as at present in use, the stratification of the materials being jigged is greatly disturbed and the top stratum remains in the jig for a greater period of time than is necessary, thereby interfering with the proper operation of the jig and causing imperfect separation of the waste constituents from the valuable constituents in the material being jigged.

By my present invention, I furnish a means whereby the entire top stratum is gradually carried from the receiving end of the jig to the discharge end without interference with the descent by specific gravity of the heavier constituents in the material being jigged as they become separated from the constituents in the top stratum.

Figure I is a vertical longitudinal section taken through my improved jig. Fig. II is an enlarged view partly in end elevation and partly in cross section. Fig. III is an enlarged elevation of a fragment of one of the main sprocket wheels used in the conveyer lifting mechanism and with the shaft upon which said sprocket wheel is mounted shown in cross section, taken on line III—III, Fig. II. Fig. IV is an elevation of the wrench portion of the crank arranged for engagement with the sprocket wheel and shaft shown in Fig. III. Fig. V is an enlarged elevation of the conveyer operating mechanism. Fig. VI is a horizontal cross section taken on line VI—VI, Fig. V. Fig. VII is an enlarged vertical cross sec-

tion taken partly through the frame of the jig box and one of the chutes pockets. Fig. VIII is a horizontal cross section taken on line VIII—VIII, Fig. VI. Fig. IX is an enlarged section through a portion of the jig box frame, one of the rest bars that receive the conveyer frame and the means for adjusting said rest bar. Fig. X is a diagrammatic view of one of the eccentrics by which the jig box is operated. Fig. XI is an enlarged side elevation of the top members of the conveyer operating mechanism. Fig. XII is a top or plan view of the parts shown in Fig. XI. Fig. XIII is a vertical longitudinal section of a jig differing in form from that illustrated in Figs. I to XII inclusive and with my invention applied thereto. Fig. XIV is a vertical cross section taken on line XIV—XIV through the jig shown in Fig. XIII.

In the accompanying drawings: 1 designates the water tank of my jig within which is contained a series of bins 2 that are separated from each other by partitions 2' and are adapted to contain water as usual.

3 designates a reciprocating jig box that is loosely positioned within the tank of the jig to move vertically therein and which is provided with a perforated bottom or concave screen 4, also with a screen plate 5 located at a higher elevation than the bottom or screen 4 in the plane of the entire top stratum of the material and at the discharge end of the jig above the final bin 2 and up and over which the tailings are discharged from the jig. 6 is a feed spout or feed hopper through which the material to be jigged is delivered into the jig box. The jig box has vertical reciprocation imparted to it, in order that the material in the jig box may be agitated by the movement of water through the perforated bottom or screen of said jig box.

The means just mentioned comprises the following parts: 7 are straps attached to the sides of the jig box and which are connected to vertically disposed rods 8 that are attached at their upper ends to yokes 9 that are fitted to adjustable eccentric disks 10. The eccentric disks 10 are mounted upon rock shafts 11 journaled in suitable bearing boxes mounted on the frame work of the jig above the jig box, there being preferably two of said rock shafts extending longitudinally of the jig, one at each side thereof. In order that the eccentric disks may have

an oscillatory or rocking motion imparted to them within the yokes 9 to cause the desired up and down movement of the jig box 3, I attach to each eccentric carrying rock shaft 11 a lever arm 12, see Figs. I and II to which are united connecting rods 13. The connecting rods 13 are in turn fitted to a lever arm 14 attached to a drive shaft 15 equipped with a belt wheel 16 to which power may be transmitted from any suitable source. It will be seen that when the drive shaft 15 is operated, reciprocatory motion will be imparted to the connecting rods 13 and said connecting rods act to impart a rocking motion to the lever arms 12 and the rock-shafts carrying the eccentric disks 10 with the result of causing said eccentric disks to impart the desired vertical motion to the jig box 3.

10 I now come to the description of the endless chain conveyer forming a part of my jig and which controls the delivery of the material to the jig-box and prevents the piling up of the material and by which the entire top stratum of the material delivered into the jig box is moved from the receiving end of the jig box to its discharge end without causing the bedding or lower stratum of the material deposited to travel or creep horizontally beneath the top stratum of the material deposited, while at the same time permitting free stratification of the material in the jig box. The endless chain conveyer illustrated in the drawings and which is located above the jig box comprises a pair of endless sprocket chains 17 having flights 18, made of any suitable material, solid or perforated, secured at intervals to said endless sprocket chains 17, see Figs. I and II. The lower part of the endless chain conveyer is adapted to travel in a horizontal direction above the bedding or lower stratum of the material in the jig box, so that its flights will conduct the entire top stratum in a forward direction with the result of causing this entire top stratum to be gradually discharged up and over the screen 5 at the discharge end of the jig. The endless sprocket chains 17 operate at one end upon idler sprocket wheels 19 that are carried by an idler shaft 20 and at the other end upon drive sprocket wheels 21 fixed to a driven shaft 22 that is operated by mechanism to be presently described. The endless sprocket chains of the conveyer operate in guide frames each of which comprises a lower channel bar 23 having flaring ends, an upper channel bar 24 having flaring ends (see Figs. I, II and V) and supporting bars 25 with which the channel bars 23 and 24 have slot and pin connection and which are loosely fitted to the idler shaft 20 and the driven shaft 22. The guide frame just described is loosely mounted as mentioned and its parts 65 are pivotally and loosely connected to pro-

vide for yielding of the frame when either end of the conveyer is elevated more than the other end by means to be hereinafter set forth.

During the operation of my jig the endless chain conveyer may be supported by the jig box 3 and reciprocate vertically therewith. In such instance the lower channel bars of the conveyer guide frame seat upon Z-shaped rest bars 26 having ledges 27 located adjacent to the side walls of the jig box and flanges 28 surmounting said side walls, see Figs. II, VII and IX. The rest bars 26 are adapted to be adjusted vertically for the purpose of positioning the conveyer at a desired height above the bottom of the jig box and relative to the material that is present in the jig box during the operation of the jig. To provide for the vertical adjustment of said rest bars, I utilize adjusting screws 29, most clearly seen in Fig. IX which are seated in internally screw threaded bushings 30 in the top of the side walls of the jig box and internally screw threaded shift collars 31 fitted to said adjusting screws and adapted to operate in suitable perforations in the top flanges 28 of the rest bars. There may be any desirable number of the adjusting screws 29 and the parts companionable therewith in order that the rest bars may be raised and lowered to any desired degree.

Referring now to the mechanism for operating the conveyer of the jig: 32 is a ratchet wheel fixed to the driven shaft 22 of the conveyer and which is held from retrograde movement by a detaining pawl 33. 34 is a push pawl and 35 a hook pull-pawl arranged for engagement with the ratchet wheel to impart rotation thereto and to the driven shaft 22, the said pawls being connected by the spring 36 that holds them in such positions as to maintain engagement of the points of the pawls with the ratchet wheel. The pawls 34 and 35 are pivotally connected by a pivot pin 37 to an operating rod 38 preferably jointed at 39 in order that the upper portion of said rod may move laterally relative to the lower portion when the rod is reciprocated by means to be herein-after described. The lower member of the operating rod 38 has slot and pin connection with a guide block 40 that is adjustably mounted in a guide 41 attached to one of the uprights of the frame work of my jig and by which the operating rod is so held as to cause it to maintain the pawls 34 and 35 in proper positions for engagement with the ratchet wheel 32.

It is desirable in jiggling some materials to move the entire top stratum of material only while water is passing upward through the material, and in jiggling other materials it is desirable to move the entire top stratum while the water is receding or passing downwardly through the material. In other in-

stances more satisfactory results may be accomplished by moving the entire top stratum during both the rising and falling movements of the water through the material. By employing the two pawls 34 and 35, one of which is operable as a pushing member upon the ratchet wheel 32 and the other of which is operable as a pulling member upon said ratchet wheel, I provide for an intermittent actuation of the ratchet wheel and the conveyer of the jig upon both the downward and upward strokes of the operating rod 38. Either of said pawls may be thrown out of operative position, however, so that the other pawl alone will be operative upon the ratchet wheel and to permit of either pawl being moved out of its operative position, I mount in the operating rod, threaded stems 42 protecting laterally from the said operating rod and extending through lugs on the heels of the pawls and place upon the projecting ends of the threaded stems 42 thumb nuts 43 for engagement with the lugs on the heels of the pawls, in order that the points of the pawls may be retracted from the ratchet wheel.

44 designates a bell crank lever loosely mounted upon one of the rock shafts 11 at its end adjacent to the upper end of the pawl operating rod 38 and to one arm of which is attached a loop 45 that receives the upper member of the operating rod and is adjustably held therein by a set screw 46, see Figs V, XI and XII. The other arm of the bell crank lever 44 has loosely fitted to it a connecting rod 47 that unites said bell crank lever to a crank arm 48 carried by the main drive shaft 15 of the jig. During the operation of the jig, the bell crank lever 44 is rocked to and fro by reason of its connection to the main drive shaft and as a consequence, it acts to impart vertical reciprocation to the pawl operating rod 38, wherefore by either or both of the pawls 34 and 35 are caused to impart continuous intermittent movement to the ratchet wheel 32, driven shaft 22 and the conveyer operated by said members. In Figs. II and XI I have shown in the arm of the bell crank lever 44 to which the loop 45 is applied, a slot 44' and the loop is connected to said arm by a bolt that may be adjusted in said slot longitudinally of the arm. By this construction, I provide for the impartation of different lengths of strokes to the operating rod 38 and its pawls, and variations in the operations of the conveyer of the jig, according to the adjustment of the loop on said lever arm, irrespective of the speed at which the main driving shaft 15 is operated. It is obvious that the same result may be accomplished, if desired, by providing an adjustable connection between the connecting rod 47 and the arm of the bell crank lever 44 to which said rod is attached.

I provide in my jig means whereby the conveyer may be elevated to be operated at a greater elevation than that provided for when it is supported by the rest bars 26. This means also serves to support the conveyer sufficiently above the jig box to permit ready access to the jig box for the purpose of cleaning its screen.

49 and 50 designate drum shafts mounted in suitable bearings supported by the framework of the jig and extending transversely of the jig. These shafts have fixed to them above the frames of the conveyer, drums 51.

52 are suspension chains attached to the drums 51 and having connection at 53 with journal boxes 54, see Fig. II, that are slidably positioned in guides 41. The guides 41 are secured to end uprights of the frame of the jig and said boxes receive the idler shaft 20 and driven shaft 22 around which the conveyer of the jig operates.

56 designates a sprocket wheel loosely mounted upon the drum shaft 49 near one of its ends and in the outer face of the hub of which is a non-circular socket 57, see Figs. II and III. The shaft 49 is provided at its end which is adjacent to the sprocket wheel 56, with a non-circular head 49^a the shaft being cylindrical between said head and the non-circular socket in the sprocket wheel 56. The head 49^a of the shaft 49 and the socket in the sprocket wheel 56 are adapted to receive the wrench head *a* of a crank A by which the shaft 49 and the sprocket wheel 56 may be rotated in unison, or by which either of said members may be rotated independently of the other. The shaft 49 has fixed to it adjacent to the sprocket 56 a ratchet wheel 58 that is engaged by a detaining pawl 59 which serves to prevent retrograde rotation of said shaft.

60 is a sprocket wheel fixed to the drum shaft 50, and 61 is an endless sprocket chain leading from the sprocket wheel 56 to said sprocket wheel 60 in order that power may be transmitted from said sprocket wheel 56 to the drum shaft 50. When the conveyer of the jig is to be fully elevated to any desired degree relative to the jig box 3, the crank A is so placed upon the drum shaft 49 that its wrench head *a* is fitted to the head 49^a of the shaft and at the same time present in the socket 57 of the sprocket wheel 56. Now, when the crank is rotated, the drum shaft 49 will be rotated directly by said crank and the drum shaft 50 will also be rotated due to the operation of the sprocket wheel 56, the endless chain 61 and the sprocket wheel 60 with the result of the suspension chains 52 at both ends of the jig being wound on their respective drums.

It will be seen that as the suspension chains are wound upon the drums the journal boxes 54 are elevated in the guides 41 whereby the shafts 20 and 22 are raised to

lift the conveyer to the desired degree. It should be here noted that previous to the lifting or lowering of the conveyer in the manner set forth, the operating rod 38 is freed from the loop 45 by loosening the set screws 46. I desire also to call attention to the following: When the conveyer is supported by the rest bars 26 it partakes of a vertical movement with the jig box 3 and the ratchet or feed wheel 32 moves vertically within the pawls 34 and 35. At such time the conveyer may, if desired, have movement imparted to it by securing the operating rod 38 in a fixed position through the means of the guide block 40, held in a fixed position in the guide 41, and loosening the set screw 46 so that the loop 45 may play on the operating rod, while said operating rod and its pawls remain stationary during the vertical movement of the ratchet wheel 32. In order that the conveyer may be sustained in an elevated position when it is desired to so use it for conducting the material in the jig boxes, I provide the journal box 54 with binding screws 62, Fig. II by which the journal boxes may be tightly clamped in the guides 41 to retain them in fixed positions. These binding screws so hold the journal boxes as to maintain the shafts 20 and 22 in the positions to which they have been elevated, in order that the conveyer will properly perform its function when operating in the jig box upon the material therein.

It is sometimes desirable to raise one end only of the conveyer and when this is to be done the head of the crank A may be applied merely to the head 49^a of the shaft 49 without being introduced into the sprocket wheel 56. Then, when the crank is turned, the shaft 49 will be rotated without motion being communicated to the shaft 50 and as a consequence the chains 52 that are connected to the drums of the shaft 49 will be wound upon said drums to elevate the end of the conveyer beneath said drums.

63 (see Figs. I, II, VII and VIII) designates chats pockets surmounting the partitions 2' in the tank of the jig and from which the chats that are deposited in said pockets, (in handling ore in the jig) escape through outlet chutes 63' one of which is seen in Fig. II. The chats pockets include upper boxes 64 having closed top ends and lower open ends and carried by the jig box 3. The upper boxes 64 are telescopically fitted in the portions of the chats pockets supported by the partitions 2' and in the wall of each upper box that faces the receiving end of the jig are orifices 65 of elliptical oval shape. These orifices are present in the walls just mentioned at such points as to be beneath the body of material, such as crushed ore in the jig when the jig is in operation and they may be placed either high or low in said walls so that the

chats from the crushed ore may be drawn from any portion of the bed of ore. The orifices 65 are controlled by gates 66 containing elliptical or oval shaped openings and suitably fitted to the walls of the upper boxes 64 in guide-ways. These gates are operated by links 67 attached to the gates and the crank arm 68 of the operating rods 69 mounted in the side walls of the jig box 3 as seen most clearly in Figs. VII and 75 VIII.

The orifices 65 in the walls of the chats pockets and the openings in the gates 66 which register with said orifices are made of elliptical or oval shape as stated, to furnish passage-ways for chats into the chats pockets which are approximately circular when contracted, as is desirable, and which are increased in dimensions, both vertically and horizontally, when the gates are moved to enlarge the passageways.

I wish now to make mention of the fact that in jigging various different materials it is, in order that the best results be secured, highly desirable to provide for one character of movement or stroke of the jig box for one material and another character of movement or stroke of the jig box for another material. In other words, it is, for instance, desirable in jigging one material to have the jig box move slowly at the beginning of its downward stroke, and rapidly toward the completion of the stroke, and vice versa, upon the upward stroke. In jigging another material, it is desirable to have the jig box descend rapidly at the beginning of its downward stroke and move with a decreasing speed toward the end of the downward stroke, and vice versa, on the upward stroke. Other characters of strokes, such as to be presently mentioned, are also desirable. In view of what has just been said, I provide in my jig a construction whereby variations in movements or strokes of the jig box, such as those noted, may be attained by the adjustment of the eccentric disks 10 relative to the lever arms 12, and in this connection I direct attention to a diagrammatical illustration, Fig. X.

When I desire to provide for a downward stroke of the jig box in which the movement is slow at its beginning and gradually increases in speed toward the end of the downward stroke and is fast at the beginning of the upward stroke and gradually decreases in speed toward the end of the upward stroke, I position the eccentric disks 10 and the lever arms 12 relative to each other as illustrated in full lines, Fig. X, and the movement of the center of the eccentric will be that indicated by the quadrant lines at No. 1. To provide for a stroke in which the downward movement of the jig box is first comparatively slow and increases in speed at the center of the downward stroke and

then again becomes slow with inverse movement upon the upward stroke of the jig box, I position the eccentric disks relative to the lever arms so that the centers of the disks will move in the path indicated at No. 2. 5 When the downward stroke is to be made rapid at the beginning and slow at the ending with inverse movement upon the upward stroke, the eccentric disks are positioned relative to the lever arms so that the centers 10 of the disks will move in the path indicated at No. 3 and when it is desired to cause the jig box to move rapidly at both ends of its strokes and slowly at the center of its strokes, the eccentric disks are so positioned 15 relative to the lever arms as to cause the centers of the disks to move in the path indicated at No. 4.

The various characters of movements of 20 the jig box as just previously explained may be obtained either by adjusting the eccentric disks upon their shafts to change the centers of the disks relative to the lever arms 12 or by changing the positions of the lever 25 arms upon the eccentric shafts relative to the centers of the eccentrics.

In Figs. XIII and XIV, I have shown my conveyer which is the most important part of my present improvement, applied to what 30 is known as the plunger type of jigs, to show its applicability to this form of jig. It is deemed sufficient in so far as the general construction of the plunger jig is concerned, to herein make mention only of the fact that 35 it comprises a water tank 1^a, a stationary jig box 3^a having a bottom screen 4^a and plungers X operable in suitable wells in the tank for the purpose of forcing the water into the 40 tank upwardly through the screen 4^a in the jig box 3^a. My conveyer is adapted to operate in the jig box 3^a to conduct the material therein in the same manner as that hereinbefore fully set forth and it preferably comprises elements similar to those previously 45 described, viz: the endless chains 17^a and flight 18^a, the chains being operable upon means by which travel is imparted to them to cause movement of the flights in a horizontal direction longitudinally of the jig 50 and in contact with the top strata of the material in the jig box.

I desire to add that while I have herein referred to the pockets 63 as chats pockets for the discharge of chats from ores handled 55 in the jig box of my jig, these pockets may also be used as outlets from the jig box for any components of material being jigged and lying beneath the top strata in the jig box. For illustration, these pockets may 60 serve as draw-off pockets for the waste in coal when this material is being handled in my jig.

I claim:

1. In a jig, the combination of a reciprocating jig box, an endless conveyer having

flights controlling the discharge of material from the jig box and operable upon the entire top stratum of the material delivered into said jig box so as to conduct it in a forward direction relative to the jig box from the delivery end to the discharge end, and means for raising and lowering said conveyer at both ends simultaneously relative to said jig box to regulate the space between the jig bed and the conveyer, substantially as set forth. 75

2. In a jig, the combination of a reciprocating jig box, an endless conveyer operable continually upon the entire top stratum of material delivered in said jig box and 80 which includes a driven shaft, means for operating said driven shaft comprising a ratchet wheel fixed to said shaft, a pawl for engagement with said ratchet wheel, means for raising and lowering said conveyer, an 85 adjustable operating rod to which said pawl is connected, and means for moving said operating rod, adjustably connected thereto, for operating the conveyer irrespective of its elevation, substantially as set forth. 90

3. In a jig, the combination of a reciprocating jig box, an endless conveyer operable continually upon the entire top stratum of the material in said jig box and which includes a driven shaft, means for operating 95 said driven shaft comprising a ratchet wheel fixed to said shaft, a pushing pawl and a pulling pawl engaging said ratchet wheel, means for raising and lowering said conveyer, an adjustable operating rod to which 100 said pawls are connected, and means for moving said operating rod adjustably connected thereto, for operating the conveyer irrespective of its elevation, substantially as set forth. 105

4. In a jig, the combination of a reciprocating jig box, an endless conveyer operable continually upon the entire top stratum of the material in said jig box and which includes a driven shaft, means for operating 110 said driven shaft comprising a ratchet wheel fixed to said shaft, a pushing pawl and a pulling pawl engaging said ratchet wheel, means for raising and lowering said conveyer, an adjustable operating rod to which 115 said pawls are connected, means for moving said operating rod adjustably connected thereto, for operating the conveyer irrespective of its elevation, and means whereby one of said pawls may be thrown out of engagement with said ratchet wheel, substantially as set forth. 120

5. In a jig, the combination of a jig box, a conveyer operable in said jig box, a conveyer frame in which said conveyer is operable, and rest bars for the support of said conveyer frame adjustably fitted to said jig box, substantially as set forth. 125

6. In a jig, the combination of a jig box, a conveyer operable in said jig box, a con- 130

- veyer frame in which said conveyer is operable, vertically movable rest bars on which said conveyer frame is adapted to seat fitted to said jig box, and means whereby said vertically movable rest bars may be raised and lowered relative to said jig box, substantially as set forth. 50
7. The combination, with a frame work, having a series of bins and partitions separating the bins; of the chats pockets surmounting the partitions, and having outlet chutes, a jig box having a perforated bottom, upper boxes having closed top ends, lower open ends and orifices in the walls thereof supported by the perforated bottom and telescopically fitted to the chats pockets, and means whereby the jig-box is suspended and raised and lowered within the frame work. 55
8. The combination, with a frame work having a series of bins and partitions separating the bins; of the chats pockets surmounting the partitions and having outlet chutes, a jig-box having a perforated bottom, upper boxes having closed top ends, lower open ends and elliptical orifices in the walls thereof, supported by the perforated bottom and telescopically fitted to the chats pockets, gates, fitted in guide ways on the walls of the pockets, and having elliptical openings adapted to control the orifices and to register therewith, and means whereby the jig-box is suspended and raised and lowered within the frame work. 60
9. The combination, with a frame work, and a jig box having means whereby it is suspended from the frame work; of an endless conveyer comprising a pair of endless sprocket chains carrying flights, an idler shaft, located at one end of the sprocket chains, having idler sprocket wheels, and a driven shaft, located at the other end of the sprocket chains, having drive sprocket wheels, a guide frame having lower channel bars, upper channel bars, and supporting bars, means for suspending the conveyer within the jig box, the Z shaped rest bars for the guide frame, bushings in the side walls of the jig box, and screws seated in the bushings having shift collars upon which the Z shaped rest bars are supported. 65
10. The combination, with a frame work, and a jig box having means whereby it is suspended from the frame work; of an endless conveyer comprising a pair of endless sprocket chains carrying flights, an idler shaft, located at one end of the sprocket chains, having idler sprocket wheels, and a driven shaft, located at the other end of the sprocket chains, having drive sprocket wheels, a guide frame having lower channel bars, upper channel bars, and supporting bars, means for suspending the conveyer within the jig box, the Z shaped rest bars for the guide frame, bushings in the side walls of the jig box, and screws seated in the bushings having shift collars upon which the Z shaped rest bars are supported. 70
11. In a jig, a tank, a reciprocably mounted jig box in said tank, a conveyer within said jig box adapted to remove the upper stratum of the material therein, a screen forming a bottom to said jig box, and an extension screen projecting at one end of said jig box above the bottom thereof, said conveyer extending over the length of said jig bottom and said extension screen, said extension screen conforming approximately to the path of said conveyer. 75
12. In a jig, the combination with a tank, of a reciprocably mounted jig box suspended within said tank, said jig box being provided with an upwardly and outwardly curved screen at one end thereof, a screen located in the bottom of said jig box, said curved screen overhanging the end of said tank, and a conveyer extending over the length of said screens suspended within said jig box and arranged to remove the top stratum of the material therein across said curved screen. 80
- 45 bars, the Z shaped rest bars for the guide frame supported by the jig above the jig bed, and serving to limit the approach of the jig

JOHN H. MAGEE.

In presence of—

Wm. H. WATERS,

Wm. H. BLACK.
